STOKER PIPE

Harold T. Blum, Glenmont, Ohio, assignor to
Briar Hill Corporation, Millersburg, Ohio, a corporation of Ohio

Application February 23, 1939, Serial No. 258,060

8 Claims. (Cl. 131—181)

The present invention relates to smoking pipe structures and more especially to pipe structures having an arrangement for controlling the firing of the tobacco therein.

5 An object of the present invention is to provide a pipe structure and arrangement of the members thereof for enabling a user to control, as desired, the firing of the tobacco therein.

Another important object of the present invention is to provide a pipe structure which is 10 economical to manufacture, yet can be readily cleansed, and is, at the same time, capable of providing a smoke which is cool and which has had objectionable heavy oils, tars and water vapors condensed therefrom.

A further object of the present invention is to provide a simple, economical and efficient device for controlling the supply of tobacco within a smoking pipe.

20 Other objects of the present invention will be partly obvious and in part pointed out in the following detailed description of the accompanying drawing.

In the drawing:

25 Fig. 1 is a side view of the smoking pipe comprising the present invention, part of which is shown in elevation and the remainder being a cross section thereof, showing the interior.

Fig. 2 is an enlarged detail cross sectional view 30 of the bowl portion of the pipe shown in Fig. 1 with the tobacco supporting members extended and showing a broken away portion of the threads upon two of the telescopic sections.

Fig. 3 is an enlarged detail cross sectional view 35 of the bowl portion of the present invention with the tobacco supporting means in their closed position.

Fig. 4 is a cross sectional view taken in the direction of the arrows on line 4—4 of Fig. 2, and 40 Fig. 5 is a side perspective view of a decagonal tube which forms a part of the present pipe structure, with a portion broken away to show the thickness thereof.

Fig. 6 is an enlarged detail fragmentary view. 45 Referring now more particularly to the accompanying drawing wherein like reference characters designate like members, numeral 1 designates a tubular member having substantially an L-shaped configuration and which member is to 50 be formed preferably from a lightweight metal or a plastic composition. Said member 1 is formed to correspond to a smoking pipe bowl 2 which has extending from the base thereof a stem portion 3. Said stem portion 3 has detachably connected to the free end 4 thereof a mouth-

piece 5 by means of a flange portion 7 of the mouthpiece 5 overlapping end 4 of said stem. Formed longitudinally of mouthpiece 5 is an opening or bore 6 which is in connection with the interior 8 of stem 3. At the opposite end of member 1, that is, upon the open end of bowl 2, is detachably mounted a heat insulating ring 12.

Ring 12, which may be formed from meerschaum or other heat insulating material, has located centrally thereof a bore 13, which bore 10 tapers outwardly as at 14. Beneath tapered portion 14 is connected to ring 12 at extended portion 16 thereof, a metallic threaded ring 15 which is connected to said ring 12 in any known manner such as, for example, by cooling ring 15, 15 positioning it within extended portion 16 and allowing to warm and expand into position.

The bowl portion 2 of tubular member 1 has a flange 18 extending inwardly substantially at right angles thereto and which flange has further formed perpendicular therewith a threaded ring 17. Said threaded ring 17 is sized and shaped for receiving in threaded engagement metallic ring 15 and thereby detachably connecting ring 12 upon flange 18 and the upper edge 25 of ring 17. The outer wall of ring 12 is shaped and sized in order to cooperate with the outer wall of bowl 2 in order to complete therewith the appearance of a smoking pipe bowl. Likewise, tapered portion 14 of bore 13 extends from bore 30 13 to the inner side of ring 17 and thereby forms a continuous smooth walled bore from bore 13 to the lower edge of ring 17.

Said tubular member 1 has formed in its interior face situated at the base of the bowl portion thereof a recess 31, the walls of which form a regular decagon. 35

A regular decagonal walled tube 37 preferably formed of a lightweight metal is inserted within bowl 2 through ring 17 during the removal thereof from ring 12 and the base end 35 thereof is situated within said recess 31 in such a manner that recess 31 performs the function of a socket therefor, prohibiting lateral or rotary movement thereof. Each of the ten walls 32 forming the 45 tube 37 form at their connection to one another ten corners 34. Ring 17 of bowl 2 being cylindrically shaped and tube 37 being formed of straight walls 32, it results that only the corners 34 of the tube 37 contact the ring 17 and, therefore, 50 walls 32 form with said ring 17 spaces or passages 33 therebetween and yet tube 37 is prevented from lateral movement by contact of the corners 34 with the ring 17.

An opening 40 is formed through tube 37 at a 55

- central portion of said recess 31. Positioned through said opening 40 is a section 27 of a telescopic arrangement consisting of sections 22, 23, 24, 26 and 27. Section 27 has a peripheral flange 28 formed therewith which rotatably supports section 27 within the recess 31 and, at the same time, closes opening 40. Upon the portion of section 27 extending beyond the tube member 1, there are formed a series of righthand threads 29.
- 10 Screwed upon section 27 is a knurled knob 10 having a bearing portion 11, which portion 11 contacts the outer surface of tubular member 1, thereby closing opening 40 and cooperates with peripheral flange 28 to retain section 27 in place but allowing rotary movement thereof. The inner wall of section 27 has formed therein lefthand threads 30, which threads are in threaded engagement with further threads formed upon the outer surface of a second section 26, which 20 section 26 is of a diameter and length which permits the same to be rotated to a position entirely within the bore of section 27. Likewise, sections 26, 24 and 23, which have lefthand threads 25 formed upon their outer periphery and also lefthand threads 30 formed in the upper portion of their inner wall, are in threaded engagement with one another, as shown, and are sized in order that they may be rotatably telescoped one within the other.
- 30 Reference number 20 designates a plate or disc, the edge of which forms a regular decagon and which plate 20 is capable of being positioned within and extending across the bore of tube 37 with the edge of said plate 20 being in slidable contact with the walls 32 forming the bore 36 of the tube 37. Plate 20 has extending from a central point thereof a threaded projection 21, which is in threaded engagement with a threaded section 22, which in turn is in threaded engagement 40 with threads 30 formed upon the interior wall of aforementioned section 23.

Situated within the interior 8 of tubular member 1 is tobacco or other filtering material 9 but which material 9 is excluded from within the tube 37 and fills passageway 38 formed by the interior of bowl portion 2 of tubular member 1 and the exterior face of tube 37.

- In assembling the present device, telescopic section 22 is screwed into section 23, section 23 into section 24, section 24 into section 26 and section 26 into section 27, each section being inserted through the bottom of the receiving section until the entire series of sections are nestled within section 27, as shown in Fig. 3. Plate 20, by means of projection 21, is connected to section 22 and these connected members are inserted past ring 17 until flange 28 contacts the interior face of tubular member 1, at which time knurled knob 10 by a righthand rotation, is screwed onto threads 29 of section 27 until portion 11 of the knob contacts the exterior face of tubular member 1 and is sufficiently tight thereagainst to permit the knob 10 and section 27 to rotate and yet completely enclose opening 40. Decagonal tube 27 is then inserted through ring 17 until end 35 thereof is positioned within the recess 31. Ring 12 is, by threaded engagement of metallic ring 15 with ring 17 of bowl 2, screwed into position upon said bowl 2, at which time tapered bore 14 60 will be gradually lowered until it contacts or is just within point of contact with corners 34 of tube 37. This contact of bore 14 with said corners 34 retains tube 37 within the bowl 2 and recess 31, thereby preventing lateral, longitudinal or rotary movement thereof. Fresh tobacco or other filter-

ing material is then inserted within the interior 8 of tubular member 1 and then mouthpiece 5 is connected to stem portion 3 by engagement of flange 7 thereof with end 4 of the stem 3. Reversal of the foregoing functions permits the apparatus to be disassembled in an expedient manner.

When using the smoking pipe as described herein, plate 20 is positioned within tube 37, as shown in Fig. 3. Tobacco is then placed within tube 37 upon said plate 20 until the bore 36 and a portion of the bore 13 are filled therewith. Upon a flame being applied to the tobacco and the user of the pipe drawing inwardly through bore 6 of mouthpiece 5, air will be drawn through bore 13 to supply the necessary oxygen to assist in the combustion of the tobacco within the bores 36 and 13, whereby the smoke therefrom will be drawn through openings 33, as shown by the arrows in Fig. 2, to within passageway 38 and then through the filtering medium 9, due to the suction created in the interior 8 of the tubular member 1 by the user drawing, as aforementioned, upon the mouthpiece 5. As the tobacco is consumed by burning, the user, by giving knob 10 a righthand rotation, will cause section 27 to unscrew from section 26 until the section 26 reaches the blank portions 39 of the periphery thereof, whereby rotational movement between sections 27 and 26 will thereby be stopped and upon continued righthand rotation of knob 10, section 26 in its now fixed position, will unscrew from section 24 until threads 30 contact blank portions 39 upon the periphery of section 24 and the same effect will be carried through with regard to sections 24 and 23, and 23 and 22. The unscrewing of these sections one from the other, will cause plate 20 to be progressively advanced and at the same time, due to the decagonal shape of the plate 20 and tube 37, said plate 20 will not be permitted to rotate and, therefore, will prevent the rotation of section 22, thereby assisting in the unscrewing of the sections from one another upon their respective rotational movement. In this manner, the tobacco can be continuously and progressively fed to the upper end of bore 36 and to within bore 13 whereby the smoke from the burning portions thereof will travel through openings 33 and not through the remaining portions of the tobacco within said bore 36.

Tubular member 1 being of a lightweight metal or plastic will readily conduct heat from the interior thereof, thereby cooling all smoke therein causing the condensation therefrom of objectionable heavy oils, tars and water vapors, which condensation products are absorbed by the filtering medium 9 and thereby present through the mouthpiece 5 a cool, dry smoke. The ring 12 being of a heat insulating material will retain the heat from the burning tobacco therein and will not conduct said heat to the tubular member 1 and metallic tube 37 being at all times covered with fresh tobacco, will thereby be insulated against the heat of the burning tobacco and will likewise remain relatively cool. Thus, the fresh tobacco within bore 36 will remain cool and dry until presented and also smoke stored within passageway 38 will be given a chance to cool and condense the objectionable ingredients therefrom.

When the user of said smoking pipe desires to discontinue smoking, he may give knob 10 a lefthand rotation and through the connection of said knob 10 with the sections 22, 23, 24, 26 and 27, and their threaded connection to one an-

other, plate 20 will be caused to be lowered, carrying therewith the tobacco 19 supported thereby until the tobacco is lowered within the bore 36 where it will remain for use at other times.

5. Tubular member 37 has been disclosed in the drawing having a decagonal wall, but said tube 37 may have the wall thereof partially cylindrical and with the cylindrical portions connected by substantially straight wall portions. Plate 20 10 should have the edge thereof shaped to correspond to the cross sectional configuration of bore 36 in order that the plate 20 cannot be caused to rotate while positioned therein. Also, the exterior configuration of tube 37 should be so shaped as to provide with ring 17 a passage or 15 passageway 33 therebetween.

Whereas the telescopic section as shown and described comprises four sections besides section 27, a greater or smaller number of like sections 20 may be used equally as well.

My invention is capable of considerable modification but such modification as comes within the scope of the appended claims, I deem to be within the spirit of my invention.

25. I claim:

1. A smoking pipe comprising a tubular member forming a pipe bowl and stem extending therefrom, a tube positioned within said pipe bowl, a ring detachably mounted upon said pipe bowl retaining said tube within said pipe bowl and having the bore thereof in line with the bore of said tube, an end of said tube forming a passageway with said bowl and having the bore of said tube communicating therewith, a mouthpiece detachably connected to said stem, a plate extending across and slidably mounted longitudinally of the bore of said tube, means formed by said tube and said plate preventing said plate from rotating within said tube, said tubular 35 member having an opening formed through the base of said bowl portion thereof, a series of telescopic sections in limited threaded engagement with one another and having one end thereof connected to said plate, a cylindrical member rotatably mounted through said opening being in threaded engagement with the opposite end of 40 said series of sections and said sections being capable of nestling within the bore thereof.

2. A smoking pipe comprising a pipe bowl 50 member of heat conductive material having a circular bore, a stem connected to said bowl member, a tube having a rectilinear cross sectional configuration and being positioned within said bowl member extending from the base to the top thereof, said tube having a top portion of the corners thereof contacting the interior walls of said bowl for retaining the side walls of said tube spaced from said interior walls except at said corners, a tubular ring of heat insulating material 55 detachably mounted on said bowl member above said tube with the bore thereof in line with the bore of said tube and in connection with the space between said bowl and said tube and means for progressively advancing tobacco within said tube.

3. A smoking pipe comprising a pipe bowl member of heat conductive material, a stem connected to said bowl member, a tube positioned within said bowl having one end thereof closed, 70 said bowl having the open end portion thereof formed stepped, means retaining the major portion of said tube in spaced relationship to said stepped portion of said bowl, a tubular ring of heat insulating material detachably connected 75 upon said stepped portion and having the bore

thereof in line with and above the bore of said tube and means for progressively raising and lowering tobacco within said tube.

4. A smoking pipe comprising a tubular member of heat conductive material forming a pipe bowl and stem extending therefrom, said pipe bowl having the open end portion thereof formed stepped, a tube positioned within said pipe bowl extending from the interior base to and within the stepped portion thereof, means retaining the major portion of said tube in spaced relationship relative to said stepped portion forming a passageway therebetween, a tubular ring mounted upon said stepped portion with the bore thereof in line with the bore of said tube, a portion of 10 said ring bore being flared outwardly towards 15 said ring bore being in connection with said passageway and means for raising and lowering tobacco within said tube.

5. A smoking pipe comprising a pipe bowl 20 member, a stem connected to said bowl member, a tube detachably positioned within and having a portion of the sides thereof forming a passageway with said pipe bowl, a tubular ring detachably mounted on said bowl above said tube with the bore thereof in line with the bore of said tube, said ring bore being in connection with said passageway, a plate extending across and longitudinally slidably mounted of the bore of 30 said tube and telescopic means mounted through the base of said bowl member for progressively advancing said plate longitudinally through the bore of said tube.

6. A smoking pipe comprising a tubular member forming a pipe bowl and stem extending therefrom, a tube positioned within said pipe bowl, a ring detachably connected to the open end of said bowl and retaining said tube within said pipe bowl, said pipe bowl and said tube forming a passageway therebetween which is connected to the bore of said tube, a plate extending across and slidably mounted longitudinally of the bore of said tube, telescopic means for progressively advancing said plate longitudinally 40 through the bore of said tube, an opening formed in the bottom of said bowl, a tube having a threaded bore and periphery being rotatably mounted within said opening and being in threaded engagement with said telescopic means 45 for operating the same, an annular flange carried by the periphery of said tube and rotatably seated within said bowl, said tube being capable of receiving the major portion of said telescopic means therein and a cap in threaded engagement 50 with the periphery of said tube and closing the outer end thereof.

7. A smoking pipe comprising a tubular member formed from a heat conductive material and forming a pipe bowl and stem extending therefrom, said bowl having the open end portion thereof stepped inwardly, a tube having one end thereof closed and positioned within said bowl and forming a passageway with the side walls of said bowl, means for progressively raising and 60 lowering a plate within said tube, a tubular ring formed from heat insulating material mounted upon and above said stepped portion of said bowl, the upper portion of the bore of said ring being in line with the bore of said tube and the 65 lower portion of the bore of said ring extending contiguous from the periphery of the bore of said stepped portion.

8. A smoking pipe comprising a tubular member formed from a heat conductive material and 70

forming a pipe bowl and stem extending therefrom, a tube positioned within and extending the full length of said pipe bowl, said tube and said bowl forming a passageway therebetween, a tubular ring formed from heat insulating material mounted upon said bowl above said tube and having the bore substantially in line with the bore of

said tube, the bore of said tubular ring flaring outwardly for a portion thereof placing said bore in connection with said passageway, a plate longitudinally slidably mounted with said tube bore, and means for raising and lowering said plate. 5

HAROLD T. BLUM.
